US0D1049336S

(12) **United States Design Patent** (10) Patent No.: **US D1,049,336 S**
(45) Date of Patent: ** Oct. 29, 2024

(54) **STOVE**

- (71) Applicant: **Huizhou Haorui Hardware Technology Co., Ltd**, Huizhou (CN)
- (72) Inventors: **Yong Zhang**, Huizhou (CN); **Chaosen Wang**, Huizhou (CN)
- (73) Assignee: **Huizhou Haorui Hardware Technology Co., Ltd**, Huizhou (CN)

(**) Term: **15 Years**(21) Appl. No.: **29/878,936**(22) Filed: **Jun. 29, 2023****Related U.S. Application Data**

- (62) Division of application No. 35/515,877, filed on Dec. 9, 2022 (U.S. filing date under 35 U.S.C. 384), and having an international filing date of Dec. 9, 2022, now Pat. No. Des. 1,017,009.

Primary Examiner — George J Ulsh*Assistant Examiner* — Andrea Marie McKay*(74) Attorney, Agent, or Firm* — Nitin Kaushik**CLAIM**

The ornamental design for a stove, as shown and described.

DESCRIPTION

FIG. 1 is a front perspective view of a stove, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the stove, which form no part of the claimed design.

The intended use of the stove is for heating.

1 Claim, 7 Drawing Sheets(56)
